United States Patent Office.

JOHN J. SWITZER, OF CHELSEA, ASSIGNOR TO HIMSELF AND EDWIN H. FITTS, OF NORTHBOROUGH, MASSACHUSETTS.

Letters Patent No. 91,050, dated June 8, 1869.

IMPROVEMENT IN MECHANISM FOR STOPPING THE LOOM WHEN A WARP BREAKS.

The Schedule referred to in these Letters Patent and making part of the same.

To all whom it may concern:

Be it known that I, JOHN J. SWITZER, of Chelsea, in the county of Suffolk, and State of Massachusetts, have invented a new and improved Stop-Motion for Looms; and I do hereby declare that the following is a full, clear, and exact description thereof, which will enable others skilled in the art to make and use the same, reference being had to the accompanying drawings, forming part of this specification.

Figure 1, Sheet I, represents a plan or top view of a loom provided with my improved stop-motion.

Figure 2, Sheet II, is a vertical longitudinal section of the same, taken on the plane of the line $x-x$, fig. 1.

Figure 3, Sheet III, is a side elevation of the same.

Figures 4 and 5, Sheet III, are detailed side views of weights used on the warp-threads.

Similar letters of reference indicate corresponding parts.

This invention relates to a new thread-detector and stop-motion for looms, whereby the injury to fabrics, produced by the breaking of threads, is instantly prevented by the stopping of the machinery.

The present invention is an improvement on that for which Letters Patent, No. 30,885, were granted to me, on the 11th day of August, 1868. Its advantage over that described in the aforesaid Letters Patent is, that the warp can be easier applied to a new harness than it could be where the wings are used.

A, in the drawing, represents the frame of a loom, of ordinary or suitable construction.

B is the main driving-shaft, having its bearings in the frame A, and imparting, by suitable connecting-rods, motion to the batten-frame C, which is suspended in the ordinary or suitable manner.

D D are the harness-heddles, arranged as usual, and operated by suitable mechanism.

E E are the warp-threads. They are fitted over rollers and through the heddles, as usual.

From each of the warp-threads is suspended a long weight, F, which may be made of wire or other suitable material, and which has either turned-down upper ends, as in fig. 4, or an eye, as in fig. 5. That kind which is shown in fig. 4 can be applied to the threads after the same are stretched, while the others have to be held opposite the heddle-slots, to have the threads drawn through them.

The batten is, by means of a bell-crank, G, which is pivoted to the frame A, connected with the upward-projecting arm b of a vertical slide, H, said slide working in a fixed frame, I, that is arranged at one end of the frame A, as shown. By the oscillating motion of the batten, reciprocating motion is imparted to the slide H.

From the batten projects a pin, c, that fits through a slot of the bell-crank G, as shown.

In front of the slide H is arranged, in the frame I,

another upright slide, J, which is, by means of a rod, d, connected with a lever, K, which is pivoted to the frame A, said lever being, by means of a cord, e, connected with the shipper-bar L, said shipper-bar being connected with the belt driving the shaft B, as indicated in fig. 1.

From the batten projects downward a rod, f, having a horizontal arm, through an eye, g, of a bell-crank, M, that is pivoted under the loom, as shown in fig. 1.

This bell-crank is, by means of a link or rod, h, connected with a slotted frame, N, which is arranged under the warp-threads, its slots being parallel with the threads, as shown.

During each backward stroke of the batten, the crank M will be swung, so as to draw the frame N toward the frame I.

A spring, i, serves to draw the frame N back again, during the backward motion of the batten.

Above and below the frame N are similar slotted frame, O O, which move in grooves in the stationary frames, but which are not connected with the frame N, so as to be moved by the same.

From the upper frames O projects a spring-arm, j, which is connected with or fits against a lever, k, that is pivoted to the side of the frame I.

The lever k is, by a rod, l, connected with the crank of a rock-shaft, m, that has its bearings in the frame I, as shown.

From the shaft m projects an arm, n, that fits against a hook, o, which is pivoted to the slide J.

The operation is as follows:

During the ordinary progress of the weaving-process, the frame N will be moved back and forth, and the slide H up and down. As soon, however, as a thread, E, breaks, its weight F will drop, and will fall into the frames O N O, as shown in fig. 2, thereby connecting the frames.

As soon as the batten is again drawn back, the frame N will, by means of this connection, carry the frames O O with it, and will thereby cause the arm j to swing the lever k. By this swinging motion of the lever k, the rock-shaft m will also be swung, so as to cause its arm n to be pressed against the hook o, as is clearly shown in fig. 2. The hook will thereby be pushed under the slide H, so that when that slide is moved downward, during the next forward stroke of the batten, it will strike against the shoulder of the hook, and will carry the slide J down with it.

By this downward motion of the slide J, the lever k will be swung, which will pull the cord e, so as to move the shipper-bar, to shift the belt upon the loose pulley.

Thus, as soon as a thread breaks, the belt will be shifted upon the loose pulley, and the machinery will be stopped.

After the thread has been repaired, the bar L is

moved again, to replace the belt on the fixed pulley, and to restart the machinery.

P is an arm, projecting from one of the frames O, and catching against any suitable part of the frame or mechanism, to prevent such frame O from being drawn back too far. The arm *j* might otherwise be entirely disconnected from the lever *k*.

The same springs that draw back the frame N serve also to draw back the frames O, or other separate springs may be used for that purpose.

As soon as, by the backward motion of the frame O, the arm *n* is withdrawn from the hook *o*, the latter will again drop forward, out of the way of the slide H, and all parts will again be in their normal positions.

Instead of two frames O, there may be but one, but it is better to have two, as thereby the falling pin F is retained vertically, to make a good connection of the frames N O, while with but one frame O, the needle might swing in the slot, so as not to make O move with N.

The weights F, while on the threads, may be held apart by horizontal rods R R, as shown.

Having thus described my invention,

I claim as new, and desire to secure by Letters Patent—

1. The batten C, when connected, by means of the crank G, with the slide H, and by the crank M with the slotted frame N, so as to impart reciprocating motion to the same, as specified.

2. The slotted frame N, when connected with the spring i and with the batten C, substantially as herein shown and described, and for the purpose specified.

3. The frame O, arm *j*, lever *k*, and rod *l*, combined with a rock-shaft, *m*, which has the arm *n*, substantially as described, so that by the motion of the frame O the arm *n* will be moved toward and against the hook *o*, substantially as herein shown and described.

The above specification of my invention signed by me, this 28th day of October, 1868.

JOHN J. SWITZER.
